FURRIER'S ART

Peter Holman, Virginia, Minn.

Application July 9, 1931. Serial No. 549,618

3 Claims. (Cl. 149—28)

In the preparation of fur garments the pelts or skins are sewed together to produce a fur of the required size. The fur is then reinforced by securing it to a stay or reinforcing cloth. Heretofore the fur has been secured to the reinforcing cloth or backing by parallel rows of stitches placed about two inches apart and running in a generally transverse direction to the seams that unite the skins. This method of strengthening or reinforcing fur is not effective to a satisfactory extent, inasmuch as there may be weak places in the skin, and if there be such weak places between the rows of stitching this method of reinforcing the fur is not sufficient to insure against ripping of the skin in case of stress transversely of the rows of stitches.

The object of the present invention is to provide a simple, effective and inexpensive method of reinforcing fur.

The accompanying drawing is a cross section through a piece of reinforced fur, the scale being enlarged for the sake of clearness.

In the drawing, 1 denotes the skin or leather, and 2 indicates a reinforcement which may be of fabric. The skins and the reinforcing fabric are secured together by means of a layer or film 3 of latex, that is to say, the sap of the rubber tree. The latex may contain from 33% to 60% of solids. Before using, a suitable quantity of a filler such, for example, as carbon black, lampblack, or litharge, is thoroughly mixed with the latex. While the percentage of filler may vary, satisfactory results may be obtained by using about 5% of carbon black to 95% of latex. The use of the filler causes the rear side of the reinforcing fabric to lose its tackiness within a few hours. The filler also thickens the latex so that if there be small holes in the skin an objectionable amount of latex will not flow through the holes.

In practice, the pelt and the reinforcing cloth are made wet (not merely dampened). The pelt is then stretched and nailed, after which the cloth is stretched over the pelt and fastened to the nails.

The latex is then applied to the cloth and soaks through the cloth and causes the latter to adhere to the pelt. This is the preferred method, as if the latex were applied to either the pelt or the fabric separately it might set or dry to an injurious extent before the pelt and fabric could be properly applied one to the other. However, I do not desire to limit myself to this precise modus operandi.

One object in wetting the skin and the reinforcing cloth before applying the latex is to facilitate the spreading of the latex in a thin layer

before it can dry onto the hand or implement of the operator.

The skin and the reinforcing cloth having been united by the film of latex, it is permitted to dry for a few hours or over night before the fur is used in the manufacture of a garment.

If desired, after the pelt has been reinforced and become dry, talcum powder or the like may be sprinkled over the backing to prevent any remote possibility of its becoming tacky.

It will be understood that the method herein disclosed may also be used in repairing fur garments.

It will be apparent that by the use of my improved method, the entire area of the skin or leather is secured to the backing or reinforcing, and that consequently all portions of the skin are effectively reinforced and the fur rendered substantially rip-proof, whereas by the former method of reinforcing furs the fur was secured to the backing only along the lines of stitching and therefore was liable to tear in the regions between rows of stitching. By my method the fur is reinforced against stress in any direction.

The latex remains flexible for years, consequently the fur is soft and pliable throughout the life of the garment. Moreover, this method of reinforcement is less expensive than the method employing stitching. The added weight, due to the use of latex, is so slight as to be of no consequence.

Patent No. 1,029,858 granted June 18, 1912, to E. E. Evers, purports to disclose a method of producing a fur from skins that are unfit for use in fur garments, the skins being first water-proofed and being then cemented to a water-proofed backing of leather or fabric by means of rubber dissolved in a volatile solvent. The water-proofing of the skins was to be effected by a solution of rubber in benzine. This method would be much more expensive than my method because of the greater number of operations.

The Wasserman Patent No. 1,637,885, dated August 2, 1927, discloses a process which includes the steps of stretching a "plate" or fur sheet, allowing it to dry, then removing the dried sheet from the stretching board and transferring it to another board where it is fastened down, after which a reinforcing sheet is cemented to the plate. As distinguished from this method, I cement the reinforcing sheet to the plate immediately after the stretching operation and while the plate is still wet, thus reducing the amount of handling and economizing in the use of nails and cement.

I claim as my invention:

1. In the repair or manufacture of a fur garment, the successive steps of juxtaposing a wet and taut skin and a wet and taut backing cloth, applying a water carried latex base adhesive to the wetted materials, and allowing the whole to dry.
2. In the repair or manufacture of a fur garment, wetting a skin and a backing cloth, juxtaposing one upon the other in stretched condition, spreading latex on the cloth, the latex soaking

through the cloth and causing the latter to adhere to the skin, and allowing the whole to dry.

3. In the repair or manufacture of fur garments, wetting a skin, stretching the skin and securing it in stretched condition, placing a wet backing cloth upon the skin while the skin is still wet, securing the cloth in stretched condition, spreading latex on the cloth, the latex soaking through the cloth and causing the latter to adhere to the skin, and allowing the whole to dry.

PETER HOLMAN.
